UNITED STATES PATENT OFFICE.

FRANK IUCULANO, OF NEW YORK, N. Y.

DESIGN FOR A PHONOGRAPH.

58,148.

Specification for Design. Patented June 14, 1921.

Application filed April 21, 1920. Serial No. 375,633. Term of patent 3½ years.

To all whom it may concern:

Be it known that I, FRANK IUCULANO, a citizen of Italy, and a resident of the city of New York, borough of Manhattan, in the county and State of New York, have invented a new, original, and ornamental Design for a Phonograph.

Reference is to be had to the accompanying drawing, in which—

The figure is a front view of a phonograph showing my design.

What I claim is,

The ornamental design for a phonograph as shown.

FRANK IUCULANO.
